US0D1102622S

(12) **United States Design Patent** (10) **Patent No.:** **US D1,102,622 S**
(45) **Date of Patent:** **** Nov. 18, 2025**

(54) **HOLDER**

(71) Applicant: **MASIMO CORPORATION**, Irvine, CA (US)

(72) Inventors: **Ammar Al-Ali**, San Juan Capistrano, CA (US); **Chad A. DeJong**, Los Angeles, CA (US); **Hee Seung Lim**, Irvine, CA (US); **Austin Kretz Pike**, Laguna Niguel, CA (US)

(73) Assignee: **Masimo Corporation**, Irvine, CA (US)

(**) Term: **15 Years**

(21) Appl. No.: **29/899,036**

(22) Filed: **Aug. 3, 2023**

(51) LOC (15) Cl. **24-02**

(52) U.S. Cl.

USPC **D24/227**

(58) **Field of Classification Search**

USPC D24/169, 173, 170, 177, 185, 186, 187, D24/216, 224, 227, 231, 107, 167-168
CPC G01N 2223/301; H02J 7/0044; A61L 2/26; B65D 85/38; B65D 75/327; A61B 50/30; A61B 50/33

(57) **CLAIM**

The ornamental design for a holder, as shown and described.

DESCRIPTION

FIG. 1 is a front perspective view of a holder embodying our new design;

FIG. 2 is another front perspective view thereof;

FIG. 3 is a rear perspective view thereof;

FIG. 4 is another rear perspective view thereof;

FIG. 5 is a front view thereof;

FIG. 6 is a rear view thereof;

FIG. 7 is a side view thereof;

FIG. 8 is another side view thereof;

FIG. 9 is a top view thereof; and,

FIG. 10 is a bottom view thereof.

Broken lines, where shown, are used to illustrate portions of the holder that form no part of the claimed design.

1 Claim, 7 Drawing Sheets
